SATELLITE COMMUTATOR HAVING REED
RELAY MATRIX

Arthur F. Hogrefe, Silver Spring, Md., assignor to the
United States of America as represented by the Secretary
of the Navy

Filed May 7, 1963, Ser. No. 278,793
8 Claims. (Cl. 340—166)

This invention relates in general to time multiplexing equipment and, more particularly, to an electro-mechanical commutator utilizing reed relays in its connection matrix.

The present invention generally resembles commutating equipment which is well-known and has existed for many years. However, the instant invention includes several additional unique features which render it singularly suitable for application in satellite systems. More specifically, it employs reed relays for making successive connections, and controls the operation of these relays by reliable electronic circuits, thereby combining the advantages of both electronic circuits and mechanical devices.

The instrumentation of the electronic circuits of the present invention includes safety features for eliminating any interaction between satellite monitoring systems, in the event of any catastrophic malfunction during launch affecting the interconnection of any two or more channels of the commutator. Additionally, the instant invention is designed to operate on a 75% duty cycle, thereby reducing power drain and, more importantly, facilitating the design of ground equipment which is used in conjunction thereto.

Another beneficial feature resulting from the employment of electronic control circuitry is the use of a series of connected flip-flops as counters, which flip-flops have one of their stages connected to a common inhibiting current source. This current source acts as a safety feature whereby only one flip-flop can be energized at a time in contradistinction to the use of a voltage level, which level allows the energizing of more than one stage under noisy operating conditions. Such a spurious operation persists indefinitely until reset by turn off of the ring counter, and causes the loss of information during that period. Also, the flip-flop ring counters of the present invention have bias networks to prevent a complete circuit failure upon a momentary loss of the single existing excited flip-flop due to noise. These networks automatically cause the first stage of each of the counters to be turned on and allow normal operation to begin again.

The mechanical advantages lent to the instant invention through the use of reed relays include complete isolation between the separate satellite systems which are gathering information, and a resulting absence of cross talk between channels. Therefore, a commutator can be made with any number of channels without any inherent limit. Additionally, the use of the reed relays permits the sensing of signals 100 to 1000 times smaller than is possible with the use of an electronic connecting matrix.

One object of the present invention, therefore, resides in the provision of a satellite commutator which is suited for remote operating conditions by the use of built-in safety features.

Another object of the invention is to provide a satellite commutator which exhibits zero cross talk and provides sufficient isolation between input channels.

A further object of the invention is to provide a satellite commutator which is able to resolve very small input signals.

A still further object of the invention is to provide a satellite commutator which allows the employment of high accuracy ground equipment.

2

Other objects and many of the attendant advantages of this invention will be readily appreciated as the same becomes better understood by reference to the following detailed description when considered in connection with the accompanying drawings, wherein:

FIG. 1 is a generalized block diagram of the instant invention;

FIG. 2 is a schematic diagram of the current source, bias network and first counter stage of the X-axis driver shown in FIG. 1;

FIG. 3 is a schematic diagram of the current source, bias network, first counter stage and positive amplifier employed in the Y-axis driver;

FIG. 4 is a schematic diagram of the reed relay matrix employed in the instant invention showing how an individual relay is energized; and

FIG. 5 shows typical relay circuits employed in the instant invention.

Briefly, the instant invention comprises a reed relay matrix for connecting the output of various electronic circuits dispersed within the satellite, which circuits monitor the functioning of the satellite at selected points. The connecting matrix is driven by a pair of counters which sequentially energize the relays in the matrix, which counters in turn are synchronized and driven by a clock and drive circuit. In operation, the clock and drive circuit may either free run or be synchronized to an external source of extreme timing accuracy. However, the embodiment shown is free running.

Referring to FIG. 1, the clock and drive circuit 1 employed in the instant invention has three output signals, the first of which is connected to an X-axis driver 2, which driver includes a plurality of counters 3, the second is connected to a Y-axis driver 4, which driver includes a plurality of counters 5, and the third is connected to a plurality of positive amplifiers 7. The counters 3 are consecutively connected together and form a one to six counter, while the counters 5 are connected together and form a one to five counter. The outputs of the counters 3 directly drive the X-axis of a reed relay matrix 9, while the outputs of the counters 5 are first connected to the amplifiers 7 for the proper polarity inversion before being applied to the Y-axis of the matrix. Only one of the lines from each of the counters 3 and 5 is energized at any time. A relay positioned in the matrix 9 and located at the intersection of the pair of energized lines is activated, thereby connecting one output of a satellite monitoring circuit to the satellite transmitting equipment for transmission to the ground.

For clarity in the relay matrix 9, shown schematically in FIG. 1 and in greater detail in FIG. 4, the lines drawn horizontally will be designated "rows," whereas those arranged vertically will be called "columns."

The clock and drive circuit 1 contains features whereby it may either be free running or synchronized to an external source. A pair of cascaded amplifiers 14 and 16 take an external repetitive synchronizing signal when applied to an input terminal 17 and apply it to an astable flip-flop 18, which flip-flop would also free run in the absence of the input synchronizing signal. The flip-flop 18 has two output signals, one of which is applied to a divide by 2 flip-flop 20, and the other is applied to a gated amplifier circuit 22. The flip-flop 20 produces an output signal at a rate one-half its input signal, which output signal is also applied to the gated amplifier 22. The two input signals applied to the input of the amplifier 22 are combined at its input in the form of a logical "or" gate operation so that the output signal has a duty factor of 75%.

The output from the amplifier 22 is applied to a drive amplifier 24, which amplifier increases the power of its

input signal and applies its output signal to a one-shot flip-flop 26 and a gate drive amplifier 28. The one-shot flip-flop 26 develops the drive pulses for advancing both the counters 3 and 5, while the drive amplifier 28 produces the gating signal applied to the positive going amplifiers 7 and produces the 75% duty factor for the reed connecting matrix 9. The flip-flop 26 is connected to a current source 29 employed in both the X-axis and Y-axis drivers 2 and 4, which drivers additionally employ bias networks 30 connected to voltage source terminals 31 and to the first counter stages of each of the drivers.

One of the current sources 29 for the counters 3 is shown schematically in FIG. 2, and includes a pair of transistors 32 and 33. A base lead 34 of the transistor 32 is connected to ground 35 by a series connected resistor 36 and diode 37, which diode 37 is connected so as to maintain a slightly positive signal at its junction with the resistor 36. Additionally, the base lead 34 of the transistor 32 is connected to the source of positive potential 31 by a series connected diode 38 and resistor 39, which source 31 may be a positive 22 volts, and which diode 38 is connected so as to allow a flow of biasing current from the source 31 to ground 35 through the divider 39, 38, 36 and 37. A capacitor 40 is connected in parallel with the series connected diode 38 and resistor 39. An emitter lead 41 of the transistor 32 is connected to the base lead 42 of the transistor 33 and a collector lead 43 of a transistor 32 is connected to a collector lead 44 of the transistor 33. The emitter lead 41 of the transistor 32 is connected to the potential source 31 by a resistor 45, and an emitter lead 46 of the transistor 33 is connected to the potential source 31 by a pair of parallel connected resistors 48 and 49. The values of the resistors 48 and 49 are chosen to obtain a 16 volt level at the emitter lead 46 of the transistor 33 when one flip-flop only is conducting.

The biasing network of the first counter 3 is used to reset the first counter whenever the one "on" stage of the X-axis driver is lost, and comprises a pair of resistors 50 and 51, a capacitor 52, and a diode 53. The resistors 50 and 51 are connected in series with an additional resistor 54 between the potential source 31 and ground 35. The capacitor 52 is connected from the junction of the resistors 50 and 51 to ground 35, and the diode 53 connects a base lead 55 of a transistor 56 to the junction of the resistors 50 and 51, and functions to pass negative signals to said base of the transistor 56.

The remaining circuitry for the first flip-flop counter stage is identical for the additional five counter stages, which stages include, in addition to the transistor 56, a second transistor 57, which transistor has a diode 58 connected in parallel between its collector lead 60 and the source of potential 31. The diode 58 is arranged to maintain the voltage level of the collector 60 below the level of the voltage source 31. An output terminal 61 is connected to the collector lead 60 of the transistor 57 by a line 62, which line constitutes a drive line for one of the columns in the matrix shown in FIG. 4. Succeeding counter flip-flops 3 energize the remaining columns of the matrix 9 by means of identical lines 62'. An emitter lead 65 of the transistor 57 is connected to the junction of the resistor 36 and the diode 37 by a line 66, and is also connected to the emitter lead of the corresponding transistor in the next counter stage by a line 68. A base lead 70 of the transistor 57 is connected to ground 35 by a resistor 72, and to a collector lead 76 of the transistor 56 by a resistor 74. The input signal from the one-shot flip-flop 26 is applied to the collector lead 44 of the transistor 33 by a line 78, and said collector lead 44 is connected to an emitter lead 79 of the transistor 56 by a line 81 and to each succeeding emitter leads of corresponding transistors in the following counter stages by a line 82. A series connected diode 83 and

capacitor 84, a line 85 and a diode 86 connect the collector lead 76 of the transistor 56 to a base lead 55' of the corresponding transistor, in the following counter stage 3, and constitute the circuit over which trigger pulses pass to energize the subsequent counter flip-flop stage. The diode 83 is connected to pass positive going signals from the collector lead 76 to the base lead 55' and the diode 86' is connected to pass negative signals to the base lead 55'. A line 87 is connected between the junction of the diode 83 and the capacitor 84, and the junction of the resistors 51 and 54.

A second biasing arrangement for the first counter stage is the standard biasing arrangement for the remaining stages in the X-axis driver and comprises, in addition to the diode 86, a pair of resistors 88 and 90 and an additional diode 94. The resistor 88 is connected between the potential source 31, and the base lead 55 of the transistor 56. The diode 86' is connected in series with the resistor 90 and the diode 94 between the base lead 55 of the transistor 56 and the collector lead 60 of the transistor 57. Both diodes are arranged to pass negative signals from the collector lead 60 to the base lead 55. A resistor 96 is connected between the junction of the resistor 90 and the diode 94, and the junction of the capacitor 84, the diode 86' and the resistor 90'. A line 98 conducts the output signal from the terminal 61' of the last counter stage to the junction of the resistor 90 and the diode 86' which output signal triggers the first stage and causes continuous recycling.

FIG. 3 shows the positive amplifiers employed in the Y-axis driver, including considerable circuitry that is identical with that described in FIG. 2. Therefore the same numbers raised to the prime are used to identify components identical to those used in FIG. 2. The collector lead 60' of the transistor 57' is connected to the potential source 31' by a series connected line 100, a resistor 101 and a resistor 102. The junction of the resistors 101 and 102 is connected to a base lead 103 of a transistor 104. An emitter lead 105 of the transistor 104 is connected to the gate drive amplifier 28 by a series connected diode 106 and a line 107, and the collector lead 108 of the transistor 104 is connected to ground 35' by a resistor 109 and to the first "row" of the reed relay matrix 9 by a line 110. Succeeding positive amplifiers 7 energize the remaining "rows" of the matrix 9 by lines as shown in FIG. 1.

FIG. 4 shows the "rows" and "columns" contained in the connecting matrix 9 employed in the instant invention. Each "column" of the matrix is energized by a separate line 62 or 62' from one of the counter stages 3 contained in the X-axis driver 2, and each "row" is energized by a separate line 110 or 110' from one of the counter stages 5 contained in the Y-axis driver 4. Since the drivers 2 and 4 each employ a mutually prime number of counters, which numbers have no common factor other than one, the relays are energized in the order indicated in FIG. 4 by consecutive K numbers K1 through K30.

A typical relay energizing circuit 114, shown in FIG. 4, comprises a diode 115 in series with an individual relay coil 17, which elements 115 and 117 are connected between the lines 110 and 62, and a diode 119 connected across the relay coil 117 to provide damping. However, sometimes a capacitor is substituted for the diode 119 to allow an oscillatory damping and to prevent sticking of the relay contacts. A suitable reed relay is that identified as type 532-1, manufactured by Struthers-Dunn Company. Because of the number of counters employed in the X-axis and Y-axis driver in the embodiment of the instant invention, the reed relay matrix shown has a capacity of 30 channels and a requirement for an equal number of energizing circuits 114, however only 3 representative circuits are shown.

Referring to FIG. 5, there can be seen a pair of typical relay circuit arrangements including a relay contact arm 120, an input resistor 121, and a load resistor 122. When

the relay contact arm 120 closes, the signal from one of the monitoring circuits is transferred to the output terminal 123 for transmission over the satellite transmission system. The resistors 121 and 122 reduce the signal amplitude for proper signal transfer within the system range. The values of these resistors 121 and 122 depend upon the type of monitoring circuit to which it is connected but are easily determined according to well-known design principles; however, the resistor 121 should be larger than 1000 ohms to prevent interaction of separate satellite monitoring systems, which interaction occurs upon the simultaneous unintentional closure of two or more relay arms 120.

In operation, the free running flip-flop of the clock and drive circuit 1 develops a series of pulses for use as the basic source of timing pulses throughout the commutator. An additional logical "or" gating circuit 22 develops a drive waveform of about two seconds period with a 75% symmetry, that is, a waveform which is at ground potential 25% of the time and at a positive voltage potential the remaining 75% of the time. This output waveform simultaneously drives both the X-axis and the Y-axis drivers 2 and 4. Since the first counter stage 3 and 5 of each axis driver is biased in such a manner as to assume the "on" condition in the absence of any input signals, both counters will advance sequentially from the first counter stage to the last stage, which stage then resets the first stage to continue recycling. A typical counter stage 3 and 5 utilized in both the X-axis and Y-axis drivers 2 and 4 consists of the pair of transistors 56 and 57, as best seen in FIG. 2. The transistors 56 and 57 are referenced from a voltage that is derived from the current source 29, which source will sustain stable circuit conditions if, and only if, a single counter stage is in the "on" condition. These counter stages are complementary, that is, both transistors are "on" at the same time. If the second counter stage shown in FIG. 1, is "off" and the first counter stage shown schematically in FIG. 2 is "on," the following conditions are present: the capacitor 84 has a 15 volt bias on the lead connected to the diode 83 and a 20 volt bias on the lead connected to the diode 86'. Thus, there is a potential of about five volts across this capacitor and if the first counter stage is turned "off" the input side is pulled toward ground by the resistor 54 and a resulting bias of 7 to 8 volts is applied to the base lead 55' of the transistor 56', due to the divider action of the resistors 88' and 54. Such a voltage change occurs during the period when the output drive waveform from the one-shot multivibrator 26 clamps the collectors 43 and 44 of the transistors 32 and 33 to ground. The capacitor 84 begins to charge and the bias is sustained at the base lead 55' of the transistor 56', which bias causes the transistor 56' to turn "on" when the positive period of the input waveform from the one-shot multivibrator 26 releases the current source, by enabling the second counter stage to regenerate into the "on" state. The bases of the remaining transistors 55' are biased at 22 volts under the same condition and have no tendency to turn "on" while the base lead 55 of the transistor 56 is biased at 17 volts, a significantly greater potential than that allowed to turn the transistor 56 back "on" again.

The first counter stage is always turned "on" if all the other counter stages are "off," due to the special D.C. bias arrangement found only in the first counter stage, which arrangement consists of the pair of resistors 50 and 51, the capacitor 52 and the diode 53. The positive turn "on" of the first counter stage occurs when the remaining stages are "off," which condition allows the current source line 81 to rise almost to the supply voltage, therefore placing 22 volts at the emitter 79 of the transistor 56. Since the special bias arrangement places 18 volts on the base lead 55 of the transistor 56, it is biased "on."

The transistor 57 provides the regenerative action necessary to place the transistor 56 into full conduction, while the diode clamp 58, which is connected to the po-

tential source 31, is provided to protect the collector 60 of the transistor 57 in the event of improper commutator operation and large "kick voltage" from the relay coils. The diode 86' is used in the base lead 55 of the transistor 56 to prevent the turn "on" of the previous stage from placing excessive voltage across the internal base to collector junction of the transistor 56. The diode 83 prevents the voltage across the coupling capacitor 84 from feeding back into the base of the transistor 57 after it is turned "off."

The operation of the Y-axis driver 4 is identical to that of the X-axis driver 2 just described. However, each stage drives into a positive amplifier 7, as seen in FIG. 3, by the series connected line 100 and the resistor 101. The positive amplifier 7 obtains the negative voltage from the collector lead 60' of the transistor 57 and inverts it to a positive voltage signal having a magnitude of approximately the voltage source at the connection of the line 110 with the resistor 109.

Therefore, a positive signal from the line 110 in FIG. 3 and a negative signal from the line 61 in FIG. 2 are applied across the relay coil 117, as seen in FIG. 4, to energize the relay.

The instant invention is stable in operation, having a minimum of change in its timing waveforms. This stability, in addition to purposely grounding two or three consecutive channels, allows positive frame synchronizing with supporting ground equipment.

Component values which have been selected for use in a preferred embodiment of the instant invention are as follows:

R36	ohms	121K
R39	do	38.3K
R45	do	17.8K
R50, R72, R74, R90	do	31.6K
R51	do	68.1K
R54	do	8.25K
R74, R101	do	14.7K
R88	do	46.4K
R96	do	422K
R102	do	10K
R109	do	56.2K
C40, C52	μf	.01K
C84	μf	.02K
D37, D53, D58, D83, D86, D94, D106	IN	3070
D38	IN	3064
Q32, Q56		320S2
Q33, Q104		2N2303
Q57		2N1711

Obviously, many modifications and variations of the present invention are possible in the light of the above teachings. It is therefore to be understood that within the scope of the appended claims the invention may be practiced otherwise than as specifically described.

What is claimed is:

1. An electromechanical commutator circuit, comprising,
  - a first flip-flop for developing basic timing signals,
  - a second flip-flop driven by said first flip-flop for dividing in half the frequency of the basic timing signals,
  - a gating amplifier connected to the output of both of said flip-flops for performing a logical "or" function in generating a waveform having a partial duty cycle,
  - a one-shot flip-flop electrically connected to said gating amplifier for developing drive pulses,
  - a drive amplifier electrically connected to said gating amplifier for furnishing gating pulses,
  - an X-axis driver actuated by said one-shot flip-flop for sequentially developing a plurality of energizing voltages,
  - a Y-axis driver actuated by said one-shot flip-flop and controlled by said drive amplifier for sequentially developing a second plurality of energizing voltages, and

a plurality of reed relays formed as a matrix and connected to said X-axis driver and to said Y-axis driver, whereby said pair of energizing voltages is consecutively applied to each of said relays for activation thereof.

- 5 2. A commutator circuit as recited in claim 1, wherein said X-axis driver comprises,
a plurality of flip-flops connected to form a recirculating counter,
a current source connected to each of said flip-flops for 10 individually furnishing an energizing voltage to each of said flip-flops,
means for initially biasing the first of said flip-flops to conduction, and
means connected between consecutive flip-flop stages for 15 sequentially energizing the remaining plurality of flip-flops.

3. A commutator circuit as recited in claim 1, wherein said Y-axis driver comprises,
a plurality of flip-flops connected to form a recirculating counter,
a current source connected to each of said flip-flops for 20 individually furnishing an energizing voltage to each of said flip-flops,
means for initially biasing the first of said flip-flops to 25 conduction,
means connected between consecutive flip-flop stages for sequentially energizing the remaining plurality of flip-flops, and
a positive amplifier connected to each of said flip-flops 30 and controlled by said drive amplifier.

4. An electromechanical commutator circuit, comprising,
a first flip-flop for developing basic timing signals,
a second flip-flop driven by said first flip-flop for dividing 35 in half the frequency of the basic timing signals,
a gating amplifier connected to the output of both of said flip-flops for performing a logical "or" function by generating a waveform having a 75% duty cycle,
a one-shot flip-flop electrically connected to said gating amplifier for developing drive pulses,
a drive amplifier electrically connected to said gating amplifier for furnishing gating pulses,
a first plurality of flip-flops connected to form a first 40 recirculating counter for generating an energizing voltage,
a second plurality of flip-flops connected to form a second recirculating counter,
current sources operated by said one-shot flip-flop and connected to each of said plurality of flip-flops for 50 individually furnishing an energizing voltage to each of said flip-flops,

- means for initially biasing the first of said flip-flops in said first and said second counters to conduction,
means connected between consecutive flip-flop stages in 55 said first and said second counters for sequentially energizing the remaining plurality of flip-flops in each of said counters,
a positive amplifier connected to each of said flip-flops in said second counter and controlled by said drive amplifier for generating a second energizing voltage, and
a plurality of reed relays formed as a matrix and connected to said first counter and to said positive amplifiers, whereby each of said relays is consecutively activated by said pair of energizing voltages.

- 60 5. A commutator circuit as recited in claim 4, wherein said current source comprises,
a first transistor having a base, an emitter and a collector,
the collector of said first transistor being electrically connected to said one-shot flip-flop and to each of 65 said flip-flops in its respective counter,

a second transistor having an emitter, a base and a collector,
the collector of said second transistor being connected to the collector of said first transistor,
means for biasing said first transistor to conduction in the presence of a positive potential signal from said one-shot flip-flop,

the emitter of said first transistor being connected to the base of said second transistor for causing said second transistor to conduct at the same time the first transistor conducts, and
means connected to the emitter of both of said transistors for regulating the flow of current through said transistors, whereby a stable current level is set at the emitters of said transistors, which level is capable of causing only one of the counter stages to be placed in conduction.

6. A commutator circuit as recited in claim 4, wherein one of said counter flip-flops comprises,
a first PNP transistor having a base, an emitter and a collector,
the emitter of said first transistor being connected to said current source,
a second NPN transistor having a base, an emitter and a collector,
the collector of said first transistor being electrically connected to the base of said second transistor and to ground,
the emitter of said second transistor being connected to a first positive potential,
means for connecting the collector of said second transistor to a second positive voltage potential greater than said first positive potential,
means for connecting the collector of said second transistor to the base of said first transistor and to the second source of positive potential, and
means for biasing said first transistor to conduction upon operation of said sequential energizing means in transferring a triggering pulse from the first transistor of a prior counter flip-flop.

7. A commutator circuit as recited in claim 4, wherein said sequential energizing means comprises,
a capacitor electrically connected to said collector of said first transistor for charging during the period of conduction of the first counter flip-flop and for discharging during the grounding of said current source to create a trigger pulse for application to said base of said subsequent counter flip-flop,
a first diode electrically interposed between said capacitor and the collector of said first transistor on said first counter flip-flop for preventing the voltage across said capacitor from feeding back into the collector of the first transistor and that had just been on, and
a second diode interposed between said capacitor and the base of the first transistor of said subsequent counter flip-flop for preventing the turn on of said first counter flip-flop from placing excessive voltage across the base to collector junction of said subsequent counter flip-flop.

8. A commutator circuit as recited in claim 6, wherein said collector connecting means of said second transistor further includes,
a diode clamp electrically interposed between the collector of said second transistor and said second potential source for protecting said second transistor from large voltage surges caused by improper commutator operation.
